UNITED STATES PATENT OFFICE

100,750

DESIGN FOR A JAR

Lysle E. Adams, Chicago, Ill.

Application May 1, 1936, Serial No. 62,405

Term of patent 14 years

To all whom it may concern:

Be it known that I, Lysle E. Adams, a citizen of the United States, residing at Chicago, in the county of Cook and State of Illinois, have invented a new, original, and ornamental Design for a Jar, of which the following is a specification, reference being had to the accompanying drawing, forming part thereof and wherein

Fig. 1 is a side elevational view of the jar looking in the direction of the arrows on line 1—1 of Fig. 3 showing my new design;

Fig. 2 is a side elevational view thereof looking in the direction of the arrows on line 2—2 of Fig. 3;

Fig. 3 is a top plan view thereof.

I claim:

The ornamental design for a jar, as shown and described.

LYSLE E. ADAMS.
